Application July 29, 1953, Serial No. 370,972

2 Claims. (Cl. 30—106)

The present invention relates to cutters for condenser, cooler and heat exchanger tubes.

A purpose of the invention is to obtain more positive action and particularly to obtain more positive release of the cutter from the tube after cutting.

A further purpose is to make a lighter, smaller and simpler tube cutter.

A further purpose is to speed up the cutting action and obtain much more steep outward movement of the tool.

A further purpose is to reduce the drag on the collar during cutting.

A further purpose is to ream burrs out of the way during the cutting operation without requiring a separate reaming operation.

Further purposes appear in the specification and in the claims.

In the drawings we have chosen to illustrate a few only of the numerous embodiments in which our invention may appear, selecting the forms shown from the standpoints of convenience in illustration, satisfactory operation and clear demonstration of the principles involved.

Figure 1 is a longitudinal section of the preferred cutter of the invention in retracted position.

Figure 2 is a view corresponding to Figure 1 showing the cutter advanced to cutting position.

Figure 3 is a longitudinal section on the line 3—3 of Figure 1.

Figure 4 is a rear end elevation of the device of Figures 1 to 3.

Figure 5 is a staggered section on the line 5—5 of Figure 1.

Figure 6 is a section on the line 6—6 of Figure 1.

Figures 7 to 14 show a variation in the invention.

Figure 7 is a longitudinal section showing the cutter installed, ready to cut a tube, but still retracted.

Figure 8 is a view corresponding to Figure 7 showing the cutter advanced and the tube cut.

Figure 9 is a section on the line 9—9 of Figure 7, omitting the tube and tube sheet.

Figure 10 is an enlarged front view of the cutter of Figures 7 to 9.

Figure 11 is an enlarged section on the line 11—11 of Fig. 7, omitting the tube.

Figure 12 is an enlarged section on the line 12—12 of Figure 7.

Figure 13 is an enlarged section on the line 13—13 of Figure 7.

Figure 14 is a fragmentary section on the line 14—14 of Figure 11.

Describing in illustration but not in limitation and referring to the drawings:

Tubes in condensers, coolers and other heat exchangers are usually rolled into engagement with a tube sheet, and they can be very quickly installed. It is, however, occasionally necessary to remove and replace such tubes and this is a difficult operation. In common practice in removing the tube, it is cut by a tube cutter which cuts off the tube inside the tube sheet and thus permits the severed ends to be withdrawn separately. The present invention

is an improvement over tube cutters of the type disclosed in William F. Oberhuber U. S. Patent No. 1,922,630, granted August 15, 1933, for Cutter for Condenser Tubes.

Cutters of the character of that shown in the Oberhuber patent have several disadvantages. Once the tube is cut the cutter is often slow in restoring the parts to starting position, so that there is delay or difficulty in extracting the cutting edges. By the present invention a more rapid positive cam action is applied to return the cutter to its starting position to avoid this difficulty.

In the prior art cutters, the operation has often been slow, because the feed of the cutter has not been sufficiently rapid. The present invention is designed to give more rapid feed and preferably to employ a cutter separate from the cutter bar which is extending radially and can be positioned at the most advantageous angle for maximum feed.

The device of the invention also is markedly lighter and smaller than prior art cutters.

One of the features which has been inherent in prior art cutters is that a great deal of strength and energy has been required in operation. Part of this has been due to the frictional drag of the collar against the end of the tube. In the device of the invention this has been cut down by introducing an antifriction thrust bearing at this point.

In some cases obstructions on the inside of the tube make it necessary to ream as a separate operation. In one of the forms of the invention a reamer is mounted on the forward end of the cutter so that any surfaces requiring reaming will be reamed as the cutter is introduced into the tube.

Considering now the form of Figures 1 to 6 inclusive, a plug 20 which forms the main body of the device has a forward portion 21 which extends into the tube to be cut and is suitably of the largest diameter of the plug, has an intermediate portion 22 which is suitably of circular outside contour and is of slightly reduced diameter, joining the forward portion 21 in a stop shoulder 23, and has a rearward shank 24 which is adapted to be chucked in a rotary drill or other rotary tool which operates the cutter.

From a position just forward of the shank 24, a longitudinal slot 25 extends the full distance forward to the front of the cutter and is adapted to contain the cutter bar.

Surrounding the plug and normally engaging the shoulder 24 is a washer-like forward thrust bearing race 26 which is movable along the plug as shown. Rearwardly of the forward thrust bearing race 26 and providing a rearward thrust bearing race we place a collar 27 which moves longitudinally of the plug in operation. To complete the thrust bearing, balls 28 are placed between the forward race and the collar. The balls 28 are held in place by a conventional ball retainer ring (not illustrated).

The collar is desirably provided with an annular extension 30 directed rearwardly and this engages the forward end of a spiral compression spring 31, the rearward end of which is engaged by a spring abutment 32 which surrounds the plug and is adjustable along it by a set screw 33. Thus the spring tension can be regulated.

In the slot 25 and extending forwardly of the collar there is a tool bar 34 which at its forward end has a transverse opening 35 which receives a transverse radially extending cutter 36, held in place by set screw 37 which in the form of Figures 1 to 6 extends longitudinally. As shown in Figures 3 to 6, the slot 25 is desirably positioned to one side of the center so that the leading edge of the cutter 36 is radial.

The cutter bar near its rearward end has a pivot ear 38 which extends into a slot 40 of the collar. A pin 41 extends across the collar through an opening therein to pivot the cutter bar.

In the retracted position, one face 42 of the cutter bar extends longitudinally along the base of the slot, but near the forward end behind the cutter a cam portion 43 of the cutter bar deviates from the longitudinal line of the face 42 in a direction away from the cutter point, forming a cam surface which on rearward movement of the collar engages a cam surface 44 on the forward end of the slot in the plug to urge the cutter radially outwardly as shown in Figure 2. Rearwardly of the pivot 41 the cutter bar has a cam extension 45 which on the surface 46 extends convergingly toward the bottom of the slot as it moves rearwardly. Pin 47 extends across the plug near the base of the slot and when the cutter retracts the cam surface 46 on the cam extension 45, engages the pin and forces the cutter radially inwardly. This therefore gives very effective retraction of the cutter. The collar 27 is slotted at 47' to permit insertion of the pin 47.

In operation of the form of Figures 1 to 6, with the parts in retracted position and the shank mounted in the chuck of a drill, the forward portion 21 of the plug and the cutter and the forward part of the cutter bar are inserted in the tube to be cut. When pressure is applied with rotation after starting the electric drill or other tool, the thrust bearing race 26 engages the end of the tube and the thrust bearing permits rotation of the cutter without serious frictional drag since the friction is reduced by the bearing balls 28. As the collar moves rearwardly in Figure 2 the engagement between the cam surfaces 43 on the cutter bar and 44 on the plug urge the cutter radially outwardly, and the tube is cut. When the cutting operation is complete the operator releases the pressure and allows the spring 31 to force the collar forward. At this time pin 47 encounters cam surface 46 and positively forces the cutter bar to the retracted position.

In the above operation, very rapid feeding is accomplished and this can be done without damage to the cutter since the cutter is directed radially outwardly and is not merely inclined. Comparatively little strength is required because the drag previously experienced between the collar and the end of the tube is largely avoided.

The forward race 26 of the thrust bearing need not turn and ordinarily will not.

In the form of Figures 7 to 14 a reamer is provided to ream any burrs in the same operation, and the reamer is used as one of the cam surfaces to retract the cutter bar. As seen in Figure 7, a tube 48 to be cut extends through a tube sheet 50 and has been rolled at 51 to engage the tube sheet and flanged at 52 at the outer end.

In this form the plug 20' has a forward portion which is of reduced diameter at 53, and receives a tubular reamer 54 which makes a forced fit and has outer fluted portion 55. At a position still inside the tube during cutting, the forward portion of the plug is enlarged at 56 to form the stop shoulder 23. The thrust bearing including the collar, the spring abutment and the spring are suitably the same as in the other form. The slot 25' extending longitudinally through the plug in this form involves a straight slot portion 57 which extends to a position near the tool, then a tool feeding cam 58 and then a recess 60 toward the forward end which allows the tool to move inward.

The tool bar in this form is straight for a considerable distance forward of the ear 38, but forward of the tool receiving opening 35 which mounts the radially extending tool 36 there is on the outside a retraction cam 61 which during the retraction engages the inner edge 62 of the reamer. The set screw 37' which holds the tool in this case extends in from the side of the tool bar instead of from the end.

In operation the procedure in Figures 7 to 14 is the same as that of Figures 1 to 6 except that in Figures 7 to 14 the rear surface of the tool itself engages the feeding cam surface 58 as seen in Figure 8 in advancing the tool, and on retraction the retracting cam surface 61 at the

outside near the forward end of the tool bar engages the inside of the reamer at 62 to retract the tool. The reamer functions during the early stages of cutting to remove any burrs and allow the cutter to achieve the required position in the tube.

In view of our invention and disclosure variations and modifications to meet individual whim or particular need will doubtless become evident to others skilled in the art, to obtain all or part of the benefits of our invention without copying the structure shown, and we therefore, claim all such insofar as they fall within the reasonable spirit and scope of our claims.

Having thus described our invention what we claim as new and desire to secure by Letters Patent is:

1. In a cutter for tubes, a plug having a longitudinal slot, adapted to extend into a tube to be cut, having near its forward end an external shoulder directed rearwardly and having a shank at the rear adapted to be received into the chuck of a rotary tool, a forward thrust bearing race surrounding the plug and normally engaging the shoulder, a collar surrounding the plug rearwardly of the forward thrust bearing race and forming a rearward thrust bearing race, thrust bearing elements between the forward thrust bearing race and the collar, the collar, forward thrust bearing race and thrust bearing elements being movable along the plug, a spring abutment adjustably secured to the plug rearwardly of the collar, a spiral compression spring surrounding the plug and acting between the spring abutment and the collar, a tool bar extending longitudinally through the slot and having a tool mounting at its forward end, a tool secured in the tool mounting and extending radially, a pivot on the collar pivotally mounting the tool bar, cam means at the forward end of the plug acting between the plug and the tool bar to urge the tool bar outwardly when the collar moves rearwardly, a cam extension on the tool bar rearwardly of the pivot, and a pin extending across the slot secured to the plug and acting against the cam extension to urge the tool radially inwardly when the collar moves forward.

2. In a cutter for tubes, a plug having a longitudinal slot, adapted to extend into a tube to be cut, having near its forward end an external shoulder directed rearwardly and having a shank at the rear adapted to be received into the chuck of a rotary tool, a forward thrust bearing race surrounding the plug and normally engaging the shoulder, a collar surrounding the plug rearwardly of the forward thrust bearing race and forming a rearward thrust bearing race, thrust bearing elements between the forward thrust bearing race and the collar, the collar, forward thrust bearing race and thrust bearing elements being movable along the plug, a spring abutment on the plug rearwardly of the collar, a spiral compression spring surrounding the plug and acting between the spring abutment and the collar, a tool bar extending longitudinally through the slot and having a tool mounting at its forward end, a tool secured to the tool mounting and extending radially, a pivot on the collar pivotally mounting the tool bar, and cam means acting between the plug and tool bar to move the tool radially outward in one direction of relative movement of the plug and tool bar, and to move the tool radially inward on the opposite direction of relative motion.
